(Cl. D86—10)

Fig. 1 is a perspective view of a jewelry holder or similar article embodying my new design; and

Fig. 2 is a rear elevational view thereof shown in a reduced scale.

The broken line showing of a lipstick container and ear rings in Fig. 1 is for illustrative purposes only.

The characteristic feature of my design resides in the provision of a relatively low elongated miniature cart structure having an apertured upper panel for the receipt of lipstick cases or the like, and side rails spaced from said panel for holding ear rings or the like, all as shown.

I claim:

The ornamental design for a jewelry holder or similar article, as shown and described.
